US00D853481S

(12) **United States Design Patent** (10) **Patent No.:** **US D853,481 S**
Davis et al. (45) **Date of Patent:** **** Jul. 9, 2019**

(54) **COMBINATION WRISTBAND AND LABEL FORM**

(71) Applicant: **WARD KRAFT, INC.**, Fort Scott, KS (US)

(72) Inventors: **Roger Davis**, Garland, KS (US); **Gina Staudinger**, Louisburg, KS (US)

(73) Assignee: **Ward Kraft, Inc.**, Fort Scott, KS (US)

(**) Term: **15 Years**

(21) Appl. No.: **29/610,939**

(22) Filed: **Jul. 17, 2017**

Related U.S. Application Data

(63) Continuation-in-part of application No. 15/339,105, filed on Oct. 31, 2016.

(51) **LOC (11) Cl.** **19-01**

(52) **U.S. Cl.**

USPC **D19/1; D20/22; D11/3**

(57)

CLAIM

The ornamental design for a combination wristband and label form, as shown and described.

DESCRIPTION

FIG. 1 is a front view of the combination wristband and label form; and,

FIG. 2 is a back view of the combination wristband and label form of FIG. 1.

The broken lines in FIG. 1 illustrate printed indicia and form a part of the claimed design.

1 Claim, 2 Drawing Sheets
